CLAIM

An ornamental design for a photography guide for depth of field and action stopping shutter speed, as shown and described.

DESCRIPTION

FIG. 1 is a reduced front perspective view of the photography guide for depth of field and action stopping shutter speed showing my new design;

FIG. 2 is a front elevational view of the photography guide for depth of field and action stopping shutter speed;

FIG. 3 is a rear elevational view of the photography guide for depth of field and action stopping shutter speed;

FIG. 4 is a side elevational view of the photography guide for depth of field and action stopping shutter speed;

FIG. 5 is a side elevational view of the photography guide for depth of field and action stopping shutter speed, opposite from the end shown in FIG. 4;

FIG. 6 is an end elevational view of the photography guide for depth of field and action stopping shutter speed; and, FIG. 7 is an end elevational view of the photography guide for depth of field and action stopping shutter speed, opposite from the end shown in FIG. 6.
